UNITED STATES PATENT OFFICE.

CHARLES W. PEELLE, OF NEW YORK, N. Y., ASSIGNOR TO THE PEELLE COMPANY, OF BROOKLYN, NEW YORK, A CORPORATION OF NEW YORK.

ELEVATOR DOOR.

Application filed June 22, 1926. Serial No. 117,748.

My invention relates to elevator doors, and more particularly to vertically slideable doors adapted particularly for use in closing the openings in the elevator shafts of warehouses or like buildings and forming a protection against the spreading of fire through the elevator shafts from one floor of a building to another floor thereof.

Doors of the general type to which my invention relates have been extensively used for many years. Such doors heretofore have included therein an angle metal frame, the panel opening in which has been closed either by means of a corrugated metal panel or panels, in the earlier development of the art, or by a metal sheathed wooden panel or panels in the later development of the art, although at the present time corrugated metal panel doors are extensively used.

As distinguished from the corrugated metal, or the metal sheathed wooden, panel doors, the door of my present invention is provided with plate metal panels, the construction and arrangement of which being such as to afford a rigid door structure throughout under normal conditions of use while avoiding the jamming of the doors through the buckling or other distortion of the frame and panel when subjected to intense heat. Heretofore, metal plate doors have not been used in the structure of elevator doors because of the lack of flexibility in such plates, and the difficulties of mounting same in the door frames to avoid distortion of the frame of the door by the expansion of the metal plate panels in the event of fire, with the consequent jamming of the door and hindrance to the firemen in the event that access to any floor of a building is sought during or following a fire. This condition is not present in corrugated metal panel doors, since the corrugated metal sheets are ordinarily of light stock, and by reason of their corrugations will themselves yield in a manner to compensate for expansion from heat. With the metal sheathed wooden panel door there is no appreciable expansion from heat.

In an elevator door embodying my invention, the frame of the door is so constructed, and the metal plate panels are so mounted therein as to produce a firm, rigid structure in the door, during normal conditions of use, notwithstanding the severe use to which

these doors are subjected, while in the event of a fire developing temperatures sufficiently great to cause abnormal expansion of the metal plate panels, to free the panels in a manner to permit expansion thereof without distortion of the door frames.

The use of the metal plate panels and the manner of mounting same, permits all of the securing bolts to be contained between the opposite vertical planes of the door so as to present no projections into the shaft. This construction of door, by reason of the weight and the manner of mounting the panels therein, possesses insufficient weight and strength to permit the utilization of the top bar of the door for trucking heavy loads thereover, my invention contemplating a particular construction of this top bar affording the necessary reinforcement at this point without interfering with those features of the door permitting free expansion of the panels in the event of fire.

In conjunction with the other characteristics of the invention, I provide a special stop mechanism operative upon the upper section of the door to prevent the dropping of this top section in the event of the breakage of the suspension chains from any reason whatever, the trucking bar of the door having the same effect with relation to the lower section. The effective stopping of the door sections in the event of breakage of the chains, is desirable, and while devices for securing this effect have long been used, my invention, however, relates more particularly to a special construction of stop which facilitates the assembling of the rail structure in its entirety in the shop, and avoids the necessity for work by the erectors in the building shaft in locating and securing such stops during the installation of a series of elevator doors. This construction also avoids the use of extra parts in the door and possesses great permanency, strength and rigidity.

The invention consists in the novelties of construction and combination of parts hereinafter set forth and described, and more particularly pointed out in the claims hereto appended.

Referring to the drawings, Fig. 1 is a condensed view, in elevation, of a door embodying my invention; Fig. 2 is a section also condensed on the

line 2—2 of Fig. 1 but upon an enlarged scale;

Fig. 3 is an elevation of a fragmentary portion of the lower portion of a door;

5 Fig. 4 is a perspective view illustrating the top bar structure of the lower door section; and

10 Fig. 5 is a view of a modified form of securing means of the metal plate panels to the door frame.

Like numerals refer to like parts throughout the several views.

In the embodiment of my invention shown in the drawings, it is illustrated in connection with a well known type of counterbalanced elevator door having two vertically opposite and movable sections having movement in the same vertical plane. The upper section is indicated at 10, the lower section at 11, and the chains connecting these sections so as to ensure simultaneous movement thereof in opposite directions and the counterbalancing effect of each section by the other, at 12. The pulleys over which 25 the chains 12 pass are indicated at 13, one end of said chains being connected with the lower part of the upper door section 10 and the other end to a hanger bar forming a part of the top bar structure of the lower section 11.

The door sections are guided in their movements by means of shoes 14 secured to the side bars of the frames of the door sections 10 and 11 respectively, and straddling 35 a guide rail 15 one flange of which co-operates with the shoes 14 and the other flange of which is secured to what is known as a wall angle 16 firmly secured to the wall of the building structure. The shoes, guide 40 rails and wall angles are duplicated upon opposite sides of the door structure and of the door openings in the shaft. A part of the side bar of each door section shown at 45 17 consists of a vertically extending angle bar, one flange of which is secured to one flange of the angle metal stock of the frame of the door section, and the other flange of which extends parallel with and closely adjacent the wall of the shaft to form a more 50 effective barrier at this point against the passage of flame and smoke; this part of the door structure being known as a flame angle. The flame angle imparts rigidity to the side bars of the door section and also reinforces 55 the guide shoes 14.

The sections 10 and 11 each have an angle metal frame 18, one flange 19 of which extends parallel with the wall of the shaft, and the other flange 20 of which extends inwardly of the shaft. The weight and dimensions of the angle bar frame will vary with the size of the door, or the conditions of use, doors of twelve to twenty-five feet 60 requiring much heavier stock than smaller doors.

The details of construction heretofore referred to are all old and well known in this art, my invention relating to variations from the usual details of this structure permitting the utilization of metal plate panels, and the support and reinforcement of these panels in a manner to permit free expansion 70 thereof in the event of fire without distortion of the frame, to avoid looseness between the panel and the frame under normal working conditions, and to reinforce the panel structure in a manner to resist the violent impact of heavy bodies therewith.

The construction of each of the sections 10 and 11, so far as the mounting of the 80 panels therein is concerned, is identical one with the other, and only one of these sections will therefore be described, similar reference numerals being applied to the corresponding parts in the other section. 85

Extending between the upper and lower bars of the frame of the door sections, at spaced intervals, and extending from one flange 19 of these bars to the flange 19 of the other, is a T-bar 21, the foot 22 of the T 90 projecting between the flanges 20 of said upper and lower bars, and having its opposite ends extended beyond the head and turned as shown in Fig. 3 to form sections 23 bearing against said flanges respectively 95 and secured thereto in any desired manner as by means of rivets 24 as shown. The head of the T-bar 21 is thus contained substantially in the same vertical plane as the flanges 19. These T-bars impart great 100 rigidity to the frame of the section and divide the space within the frame into a plurality of parts each adapted to receive a panel.

Within the space formed by parts of the 105 frame of the door and the T-bars 21, are mounted flat metal plate panels 25, secured about the edges thereof to the flanges 19 of the metal frame 18 by means of bolts 26, the heads of which are countersunk in said 110 flanges 19 and the head of the T-bar 21 and the nuts 27 co-operating therewith, which serve to hold said plate firmly in position with relation to said frame and said T-bar.

Said bolts 26 pass through openings 28 in the plate 25 of relatively greater dimensions than the bolts, thus affording clearance for the expansion of the plates in the event of fire.

In the form of the invention shown in 120 Figs. 1 to 4, I secure rigidity of the plate 25 by providing a fusible sleeve 29 filling each opening 28 and having an opening therethrough for the passage of the bolt 26.

In this form of the invention, each nut 27 125 bears directly upon the face of the plate 25 and serves to frictionally hold same in position. This frictional engagement, while sufficient to prevent rattling of the panel plate under normal conditions of use, is 130

insufficient to resist expansion of the metal of the plate in the event of the fusing of the sleeve 29.

The dimensions of the plate 25 are such as to space the edges thereof away from the flanges 20 of the side frame and the foot of the T-bar, a distance in excess of the maximum expansion of the plate when heated.

In the embodiment of the invention shown in Fig. 5, instead of using a sleeve 29, I employ means for holding the plate in relation to the bolts consisting of an inflammable washer 30 pressed firmly into engagement with the plate by the nut 27, this washer being of a size to close the enlarged opening 28 in the plate. The effect of the sleeve 29 and the washer 30 is the same in the respect that the application of excessive heat thereto will result in the breaking down of the support between the bolts and the plate to an extent to permit the free expansion of the latter.

By the construction above described, the panels 25 and the bolts 26 and nuts 27 securing same in position, are all located within the flanges 20 of the door frame, the plates 25 being approximately three-sixteenths of an inch in thickness not only for the purpose of imparting rigidity to the door structure, but to have said plates themselves of sufficient strength to resist violent blows thereon from loaded trucks. Such plates will also withstand efforts to gain access to or from a loft by way of the elevator shaft. The flanges 20 themselves will be from two and one-half to three inches in depth, thus affording ample space within which the plates 25 and nuts 27 may be contained. This construction brings all of the parts of the door structure within the vertical plane of the edges of the flanges 20.

While the angle metal of the frame 18, particularly when reinforced by the T-bars 21, will possess considerable strength to permit the use of the so-called truckable feature in these doors, it is essential to provide a reinforcement or truck bar in the upper bar of the lower door section and to so mount it in relation to the angle metal of this top bar as to secure the desired rigidity therein.

In the form of the invention shown, the truck bar consists of an ordinary angle bar 31, the horizontal flange of which fits snugly below the flange 20 of the top bar of the lower door section 11, and the vertical flange of which extends laterally beyond the horizontal flange and across the flanges 19 of the side bars of the section 11 to an extent to constitute a hanger bar to which the shackles connected with the chains 12 are connected. The projecting ends of the bar 31 extend across the guide rail 15 and the wall angle 16 closely adjacent the inner edges of these rails so as to be engaged by the usual

adjustable stop 37. This bar 31 is secured to the flange 19 of the top bar of the door section 11 by means of bolts or rivets 32 passing through said flange 19, and through spacers 33 between said flange 19 and the vertical flange of the bar 31, these bolts drawing the flanges 19 and the vertical flange of the bar 31, tightly against said spacers. The horizontal flange of the bar 31 is positioned above the top edge of the plate 25, and is recessed to span the foot of the T-bars 21. The flanges 20 of the side bars may be recessed to permit the passage of the vertical flange of the bar 31, or this flange may be bent to pass said flanges 20. Openings 34 are provided in the plates 25 through which the rivets 32 pass, said openings being of greater dimensions than said bolts, so that said bolts will not interfere with the free expansion of the plate 25 when occasion demands. In order to permit a tight joint between the vertical flange of the bar 31, the flange 20 and the spacers 33, I provide a heat destructible washer or washers 35 between the spacers 33 and the plate 25. This washer may be made of paper, fusible metal, or any other desirable material which, when excessive heat is applied thereto, will be disturbed or be disintegrated to an extent to form looseness between the spacer and said flange.

Heretofore, for many years past, many expedients have been used for arresting downward movement of the upper door section 10 before it reaches a point materially below the meeting of the two door sections under normal conditions. In the door of my present invention, I secure this result by merely welding, or otherwise securing to the guide rail 15, a block 36 arranged in the path of movement of the lower shoe 14 upon the upper door section 10. This construction involves the addition of no parts to the door section itself, and may be readily and accurately applied to the guide rail in the shop so as to entail no additional labor in the erection of the elevator door installation. The block 36 is duplicated upon opposite sides of the door.

I have shown a lock 38 carried by the upper door section and engageable with the lower door section, this lock being of a type commonly used in counterbalanced elevator doors.

While an elevator door embodying the invention is very much heavier than doors having a corrugated metal panel or a metal sheathed wooden panel, it has very much greater durability, and frequent repairs are unnecessary since the strength inherent to the panels 25, and the great rigidity imparted to the door by these panels and the manner of mounting same, will minimize likelihood of damage to the panels or to other parts of the door by blows thereon.

from loaded or unloaded trucks, the door possessing sufficient strength to resist blows even from power driven vehicles.

The operation of the door in opening and closing is the same as with other types of vertically moving counterbalanced, or semi, or full, automatic doors, and while I have described the invention as applied to doors in which the sections have vertical movement in the same plane, it is apparent that the construction herein described is applicable to so-called pass-type doors and various types of counterweighted doors, and is also applicable to doors having only one section known as one-piece upwardly or downwardly movable doors.

Under normal conditions of use, the metal plate panels 25 lapping the flanges 19 of the angle metal frame 18, and the head of the T-bar 21 extending from one of these flanges to the other upon the upper and lower bars of the section respectively, completely close the opening in the door as well as the openings 28, through which the bolts 26 pass, at one side of the panel, the flanged nuts 27 closing said openings at the other side of the panel, the shaft side.

The T-bars 21 serve as vertical braces for the upper and lower bars of the door section, and impart great rigidity to the door structure. The extended ends of the foot 22 of the T-bar are formed by cutting away the head of this bar, thus permitting the opposite ends of this head to form a butt joint with the edges of the flanges 19 of the top and bottom bars of the door section.

The fusible metal sleeve 29 or the heat destructible washer 35, at normal temperatures will cause the bolts 26 and nuts 27 to firmly hold the panels 25 in position and against rattling. In the event of fire, however, said sleeves or said washers will be disintegrated, thus affording sufficient clearance about the bolts passing through the openings 28 to allow expansion of the plates 25, the frictional resistance between the nuts 27 and said plates being insufficient to resist the expansion force developed by the plates 25.

The trucking feature or the utilization of the top bar of the lower door section for supporting loads passing between an elevator car and the floor of a building, is required only with thick doors and is not applicable to light corrugated metal panel doors.

With the form of construction shown, however, notwithstanding that the panels set well within the shaft edge of the flanges 20, the truck bar 31 affords effective reinforcement to the projecting flange 20 of the top bar of the frame of the door, and by reason of the resistance to a tilting action of the bar, by the spacers 33, prevents possible springing of the top bar through loads upon this projecting flange. The relation of the spacers to the panels 25, the clearance afford-

ed between the horizontal flange of the truck bar 31 and the upper edges of said panels, and the use of the washers 30, permit the firm support of this bar 31 without interfering with the expansion of the plates 25 in the event of fire.

The utilization of the stop 36 co-operating with the lower shoes 14, affords an effective stop limiting the downward movement of the upper door section 10, the use of a small unbendable block of metal forming practically an integral part of the guide rail structure, and the close sliding fit of the shoes with the guide rail precluding any possibility of the escape of the door to a point below said stops either by the bending of the stops themselves or of a metal part of the frame structure of the door co-operating therewith.

It is not my intention to limit the invention to the precise details of construction herein shown and described, it being apparent that such may be varied without departing from the spirit and scope of the invention.

Having described the invention, what I claim as new and desire to have protected by Letters Patent, is:—

1. An elevator door embodying therein an angle metal frame, one flange of which extends substantially parallel with the wall of an elevator shaft, and the other flange of which extends inwardly of the shaft, a flat metal plate closing the opening in said frame, and having dimensions to space the edges thereof away from said inwardly extending flange, and bolt openings about the edges thereof, bolts of smaller dimensions than said openings passing through the flange of said frame parallel with the wall and through said openings, and heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate.

2. An elevator door embodying therein an angle metal frame, one flange of which extends substantially parallel with the wall of an elevator shaft, and the other flange of which extends inwardly of the shaft, a flat metal plate closing the opening in said frame, and having dimensions to space the edges thereof away from said inwardly extending flange, and bolt openings about the edges thereof, bolts of smaller dimensions than said openings passing through the flange of said frame parallel with the wall and through said openings, heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate.

heat destructible means clearance will be afforded for the expansion of said plate, vertically extending guides, shoes upon said frame co-operating with said guides, an angle bar, the horizontal flange of which is in engaging relation with the flange of the top bar of the angle metal frame extending inwardly of the shaft, and the vertical flange of which extends substantially parallel with the flange of the top bar of the angle metal frame extending parallel with the wall, spacers engaging said vertical flange, heat destructible washers between said spacers and said metal plate, and means engaging the vertical flange of said bar and the flange of said frame parallel therewith, and passing through said spacers and openings in said plate, said openings being of larger dimensions than said means, whereby with the disintegration of said heat destructible washers, clearance will be afforded for the expansion of said plate with relation to said spacers and said angle bar.

3. An elevator door embodying therein an angle metal frame, one flange of which extends substantially parallel with the wall of an elevator shaft and the other flange of which extends inwardly of the shaft, a T-bar extending between the top and the bottom bars of said frame and connected therewith respectively, whereby said frame is divided into a plurality of panel openings, a flat metal plate closing each opening in said frame, the dimensions of each of said plates being such as to space the edges thereof away from said inwardly extending flange and said T-bar, each of said plates having bolt openings about the edges thereof, bolts of smaller dimensions than said openings passing through the flange of said frame parallel with the wall, through said T-bar and through said openings, and heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate.

50 4. An elevator door embodying therein an angle metal frame, one flange of which extends substantially parallel with the wall of an elevator shaft and the other flange of which extends inwardly of the shaft, a T-bar having the head thereof cut away adjacent the opposite ends thereof for a distance to bring said head in the same vertical plane and in close engaging relation with the flange of the top and bottom bars of said frame which extend substantially parallel with the wall of the shaft, the foot of said T-bar having its opposite ends turned to bear upon the other flange of the top and bottom bars and secured thereto, whereby said frame is divided into a plurality of

panel openings, a flat metal plate closing each opening in said frame, the dimensions of each of said plates being such as to space the edges thereof away from said inwardly extending flange and said T-bar, each of said plates having bolt openings about the edges thereof, bolts of smaller dimensions than said openings passing through the flange of said frame parallel with the wall, through said T-bar and through said openings, and heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate.

5. An elevator door embodying therein an angle metal frame, one flange of which extends substantially parallel with the wall of an elevator shaft and the other flange of which extends inwardly of the shaft, a T-bar extending between the top and the bottom bars of said frame and connected therewith respectively, whereby said frame is divided into a plurality of panel openings, a flat metal plate closing each opening in said frame, the dimensions of each of said plates being such as to space the edges thereof away from said inwardly extending flange and said T-bar, each of said plates having bolt openings about the edges thereof, bolts of smaller dimensions than said openings passing through the flange of said frame parallel with the wall, through said T-bar and through said openings, heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate, vertically extending guides, shoes upon said frame co-operating with said guides, an angle bar, the horizontal flange of which is in engaging relation with the flange of the top bar of the angle metal frame extending inwardly of the shaft, and the vertical flange of which

extends substantially parallel with the flange of the top bar of the angle metal frame extending parallel with the wall, spacers engaging said vertical flange, heat destructible washers between said spacers and said metal plate, and means engaging the vertical flange of said bar and the flange of said frame parallel therewith, and passing through said spacers and openings in said plate, said openings being of larger dimensions than said means, whereby with the disintegration of said heat destructible washers, clearance will be afforded for the expansion of said plate with relation to said spacers and said angle bar.

6. In an elevator door, the combination

with vertically extending guide rails upon opposite sides of door openings in an elevator shaft, of a plurality of oppositely movable sections, flexible connections between said sections, a sheave adjacent the top of the upper door section about which said connections pass, each of said door sections embodying therein an angle metal frame, one flange of which extends substantially parallel with the wall of an elevator shaft, and the other flange of which extends inwardly of the shaft, guide shoes upon the opposite side bars of each of said frames straddling said guide rails respectively, a flat metal plate closing the opening in said frame, and having dimensions to space the edges thereof away from said inwardly extending flange, and bolt openings about the edges thereof, bolts of smaller dimensions than said openings passing through the flange of the frame parallel with the wall and through said openings, and heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate.

7. In an elevator door, the combination with vertically extending guide rails upon opposite sides of door openings in an elevator shaft, of a plurality of oppositely movable sections, flexible connections between said sections, a sheave adjacent the top of the upper door section about which said connections pass, each of said door sections embodying therein an angle metal frame, one flange of which extends substantially parallel with the wall of an elevator shaft, and the other flange of which extends inwardly of the shaft, guide shoes upon the opposite side bars of each of said frames straddling said guide rails respectively, a T-bar extending between the top and the bottom bars of said frame and connected therewith respectively, whereby said frame is divided into a plurality of panel openings, a flat metal plate closing each opening in said frame, the dimensions of each of said plates being such as to space the edges thereof away from said inwardly extending flange and said T-bar, each of said plates having bolt openings about the edges thereof, bolts of smaller dimensions than said openings passing through the flange of said frame parallel with the wall, through said T-bar and through said openings, heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate.

8. In an elevator door, the combination with vertically extending guide rails upon opposite sides of door openings in an elevator shaft, of a plurality of oppositely movable sections, flexible connections between said sections, a sheave adjacent the top of the upper door section about which said connections pass, each of said door sections embodying therein an angle metal frame, one flange of which extends substantially parallel with the wall of an elevator shaft, and the other flange of which extends inwardly of the shaft, guide shoes upon the opposite side bars of each of said frames straddling said guide rails respectively, a T-bar extending between the top and the bottom bars of said frame and connected therewith respectively, whereby said frame is divided into a plurality of panel openings, a flat metal plate closing each opening in said frame, the dimensions of each of said plates being such as to space the edges thereof away from said inwardly extending flange and said T-bar, each of said plates having bolt openings about the edges thereof, bolts of smaller dimensions than said openings passing through the flange of said frame parallel with the wall, through said T-bar and through said openings, heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate, an angle bar, the horizontal flange of which is in engaging relation with the flange of the top bar of the angle metal frame of the lower door section extending inwardly of the shaft, and the vertical flange of which extends substantially parallel with the flange of the top bar of the angle metal frame extending parallel with the wall, spacers engaging said vertical flange, and means engaging the vertical flanges of said bar and flange of said frame parallel therewith, and passing through said spacers and openings in said plate.

9. In an elevator door, the combination with vertically extending guide rails upon opposite sides of door openings in an elevator shaft, of a plurality of oppositely movable sections, flexible connections between said sections, a sheave adjacent the top of the upper door section about which said connections pass, each of said door sections embodying therein an angle metal frame, one flange of which extends substantially parallel with the wall of an elevator shaft, and the other flange of which extends inwardly of the shaft, guide shoes upon the opposite side bars of each of said frames straddling said guide rails respectively, a T-bar extending between the top and the bottom bars of said

frame and connected therewith respectively, whereby said frame is divided into a plurality of panel openings, a flat metal plate closing each opening in said frame, the dimensions of each of said plates being such as to space the edges thereof away from said inwardly extending flange and said T-bar, each of said plates having bolt openings about the edges thereof, bolts of smaller dimensions than said openings passing through the flange of said frame parallel with the wall, through said T-bar and through said openings, heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate, an angle bar, the horizontal flange of which is in engaging relation with the flange of the top bar of the angle metal frame of the lower door section extending inwardly of the shaft, and the vertical flange of which extends substantially parallel with the flange of the top bar of the angle metal frame extending parallel with the wall, spacers engaging said vertical flange, heat destructible washers between said spacers and said metal plate, and means engaging the vertical flange of said bar and the flange of said frame parallel therewith, and passing through said spacers and openings in said plate, said openings being of larger dimensions than said means, whereby with the disintegration of said heat destructible washers, clearance will be afforded for the expansion of said plate with relation to said spacers and said angle bar.

10. In an elevator door, the combination with vertically extending guide rails upon opposite sides of door openings in an elevator shaft, of a plurality of oppositely movable sections, flexible connections between said sections, a sheave adjacent the top of the upper door section about which said connections pass, each of said door sections embodying therein an angle metal frame, one flange of which extends substantially parallel with the wall of an elevator shaft, and the other flange of which extends inwardly of the shaft, upper and lower guide shoes upon the opposite side bars of each of said frames straddling said guide rails respectively, metal blocks permanently secured to said guide rails adjacent the meeting point of said door sections, and in the path of movement of the lower guide shoes upon the upper door section, whereby substantial movement of said upper door section below the normal meeting point of said door sections is prevented, a flat metal plate closing the opening in said frame, and having dimensions to space the edges thereof away from said inwardly extending flange, and bolt openings about the edges thereof, bolts of smaller dimensions than said openings passing through the flange of said frame parallel with the wall and through said openings, and heat destructible means interposed between said bolts and said panel adjacent said openings, whereby, at normal temperatures, said bolts will hold said plate firmly in relation to said frame, and with the destruction of said heat destructible means clearance will be afforded for the expansion of said plate.

In witness whereof I have hereunto affixed my signature this 15th day of June, 1926.

CHARLES W. PEELLE.
